METHOD FOR REMOVING WAX

Ulric B. Bray, Palos Verdes Estates, and Donald E. Carr, Naples, Calif., assignors to Union Oil Company of California, Los Angeles, Calif., a corporation of California

Application December 18, 1933, Serial No. 702,986

10 Claims. (Cl. 196—19)

The present invention relates to the art of separating wax from wax-bearing oils, and more particularly it pertains to the withdrawal of wax from filters used for such separation.

5 It is well known that the presence of wax or waxy fractions in lubricating oils produced or obtained from wax-containing crude oils lowers the quality and value of such lubricating oils. This is due to the fact that such presence of wax 10 causes the congealing of the lubricating oil at a comparatively high temperature thus preventing proper lubrication. It has therefore been the custom to remove the wax from the lubricating oil fractions containing the same. Recently, a 15 method has been developed whereby, briefly stated, the removal of the wax from the wax-bearing oils is produced by the use of propane or of similar liquefied but normally gaseous hydrocarbons, as for example liquid butane, pentane, etc. According to this method the oil to be dewaxed is mixed with a proper quantity of such liquefied but normally gaseous hydrocarbon, and the mixture is then chilled to a temperature sufficient to cause the precipitation of the wax. 20 The agglomeration of the wax from the wax-oil-solvent mixture may also be aided by treatment with electricity. The wax thus agglomerated and precipitated is then removed from the oil-solvent mixture by cold settling, filtration or 25 centrifuging. In view of the long period of time necessary for the removal of wax by the settling method, and due to the high cost of centrifuging the mixture, it has been found that the filtration method is most suitable for such removal of the 30 agglomerated wax. However, the wax cake obtained during such filtration and especially at the conclusion of the washing cycle, i. e. after the washing of the filter-cake with propane or another hydrocarbon solvent for the removal thereof from the oil still adhering to the wax, is very 35 hard and is in a state in which it is difficult to remove it from the filter plates, the particles of wax adhering tenaciously to each other and to the filter plates.

40 It is therefore an object of the present invention to provide a method of easily removing the wax precipitated on the filter plates.

45 It is another object to treat the wax filter-cake so as to admit a rapid and easy removal thereof from the filter plates.

50 It has now been discovered that the waxy phase obtained in the dewaxing of wax-bearing oils by means of liquefied propane contains a comparatively large proportion of such propane. 55 This propane is in true solution in the wax and

does not merely constitute an occluded solvent. It has been further discovered that the evaporation of such propane from its true solution in the wax leaves the latter in a porous expanded form which is easily handled. This is probably due to 5 the fact that the differential or uneven evaporation of the propane from the different layers within the filter-cake creates differential pressures therein. This in turn produces an explosive or bumping effect within the cake with the 10 result that rapid efflorescence of the wax takes place.

The present invention therefore resides in treating the wax filter-cake so as to evaporate therefrom the liquid propane or a similar liquefied but normally gaseous hydrocarbon, and thereby leave the wax in a condition in which it is readily removable from the filter plates.

The invention further resides in filtering the mixture of a waxy oil and solvent, and subsequently treating the thus produced filter-cake to evaporate therefrom the liquid solvent remaining in solution in the wax phase. This evaporation of the liquid solvent, as for example of the liquid propane, may be carried out in a variety of ways, 25 as for instance by release of pressure, by the use of vacuum, by mechanical heating, or by passing an electric current through the frame or metal parts of the filter plates or leaves.

As a specific example, a waxy oil is dissolved in 30 liquid propane or a similar liquefied but normally gaseous hydrocarbon in the proportion of about one part of the waxy oil to from three to nine parts of the diluent-solvent, this proportion depending upon the character of the oil being treated, 35 type of diluent used, degree of dewaxing desired, etc. The mixture thus obtained is maintained under a pressure sufficient to keep the diluent in a liquid state under ordinary temperatures, said pressure ranging anywhere from 25 to 200 40 lbs. per square inch. Thereupon, the solution is chilled as by lowering the pressure and vaporizing a portion of the liquefied but normally gaseous hydrocarbon used as the diluent. This chilling is carried down to temperatures sufficient to cause 45 the above-mentioned precipitation or agglomeration of the wax in the oil, such temperatures ranging from +10 F. to -40 F. depending upon various conditions such as the character of the waxy oil and of the diluent, the ratio of one to 50 the other, degree of dewaxing desired, etc. After such chilling of the diluted oil the mixture is conveyed under pressure through a filter press wherein the wax is caused to deposit in the form of a compact cake on the filter leaves or plates. This 55

filtration is preferably carried out at a pressure of about 25 to 50 lbs. per square inch, such pressures being necessary for the forcing of the oil through the wax on the filter plates. If so desired the filter-cake is then washed with a fresh quantity of liquid propane or the like to remove the last traces of oil adhering to the wax. Such washing is also carried at a filter pressure substantially equal to that mentioned hereinabove. 10 In view of the fact that the wax cake thus produced is hard, and since it is exceedingly difficult to remove it, due to its tenacity, from the filter leaves, the wax is then treated as above described to cause an evaporation of the liquid propane in 15 solution in said wax.

Thus, the filter-cake in the filtration chamber may be heated, as for example by blowing a heated gas, to a temperature sufficient to volatilize the liquid propane in solution in the wax. Also, the 20 pressure in the filtration chamber may be lowered to produce such evaporation of the propane. If necessary, a partial vacuum may be created for the same purpose. The evaporation of the propane causes a rapid efflorescence or powdering of 25 the wax, and leaves the latter in a porous and expanded form so that the removal of such wax may be carried out very easily, as by tamping on the filter plates.

It is to be noted that the heating of the wax 30 must be carried only to a temperature of evaporation of the solvent. Further heating is detrimental in that it dissolves the wax thus increasing the difficulty of its removal from the filtration chambers.

35 It is obvious that the above operations may be carried out in a number of apparatuses. However, for the purpose of explaining more fully the manner of carrying out the present process, reference will be had to the drawing, Figure I of 40 which discloses a structure for an uninterrupted dewaxing of the oil according to the process described herein, while Figure II shows a structure which may be used for the continuous filtering and removal of wax from a wax-bearing oil.

45 Referring to Figure I, the filter chamber 10 is provided with a plurality of vertically disposed filter elements 11. The oil to be dewaxed is introduced into chamber 10 through a line 12 provided with a valve 13, while the dewaxed oil is withdrawn through pipe 15 equipped with a valve 16. A line 17, having a valve 18 thereon, leads from the upper part of the structure, while a screw conveyor 20 communicates the lower end of the filter chamber 10 with a wax discharge line 21, said line 50 being also provided with a valve 22.

In operation, a waxy oil, preferably maintained at superatmospheric pressure, commingled in a proper ratio with a diluent, such as liquid propane, and chilled to a temperature at which the 60 desired amount of wax is precipitated out of solution, is introduced into filter chamber 10 through line 12. The wax precipitates on the filter elements 11, while the thus dewaxed oil-diluent mixture is withdrawn through line 15. When the 65 filter elements become clogged with wax, valves 13 and 16 on lines 12 and 15, respectively, are closed, and valve 18 in line 17 is suddenly opened to release the pressure in chamber 10. This produces an evaporation of the diluent contained in 70 the wax, thus causing the latter to become porous and easily removable from the elements 11. The wax then falls into the lower portion of chamber 10, from where it is withdrawn, as by means of a conveyor 20, to a discharge line 21. If desirable, 75 the wax on the filter elements 11 is washed with

a diluent prior to the release of pressure. Such a procedure removes from the wax any oil still adhering thereto. It is also obvious that, instead of the above-described pressure reduction, the evaporation of the solvent in the wax may be accomplished by heating the filter plates 11, as by passing an electric current therethrough.

It is sometimes advantageous, as well as desirous, to operate the dewaxing of waxy oils in a continuous manner. Figure II shows a structure which may be used for such continuous filtration, and which discloses a means for the breaking up of the compact wax deposited on a filter drum. In this figure, the wax-bearing oil is introduced under pressure through line 26 into a mixer 28 wherein it is commingled with a diluent, such as propane, brought to said mixer through line 27. The thus obtained mixture is conveyed through line 29 to a chiller 30 wherein said mixture is chilled to a temperature at which 20 the wax falls out of solution. The chilled mixture is then conveyed through line 31 into the lower portion of a filter shell 33, which encloses a rotatable perforated drum 34 having a filter element 35 on its periphery. The filtering drum 25 34 is divided into a plurality of segments by means of imperforated plates 36, these segments opening into a valve assembly located along the axis of the filter drum 34. This valve assembly 30 consists of a valve 38 connected to line 39, and valve 40 connected to line 41. Lines 39 and 41 are also provided with valves 42 and 43, respectively. The purpose of the valve assembly and of lines 39 and 41 will be described more fully hereinbelow in connection with the description 35 of the operations of the structure.

A portion of the space between the shell 33 and the periphery of the drum 34 is separated or isolated from the rest of such space by means of longitudinal plates 45 and 46. The chamber 40 47 thus produced is provided with a pressure discharge line 49 carrying a valve 50. This chamber is further provided with a wax-removing scraper 52 abutting against filter element 35, the scraped material being removed by means of a scroll conveyor 53 and conduit 54 to a wax pot not shown in the drawing. Optionally, a line 56 may be provided for the introduction of naphtha, or of a similar substance, for the washing of the wax on the filter element 35.

In operation, the oil-wax-diluent mixture or slurry is introduced into the lower portion of shell 33 through line 31, the rate of introduction of the slurry being regulated to maintain a predetermined level in said shell. The space above 55 the slurry is maintained at a pressure to prevent the evaporation of the diluent. The filter drum 34, together with the filter element, are slowly rotated. By maintaining a pressure differential across said filter element, filtration will occur 60 in the segments dipping into the slurry. The filtrate, consisting of the dewaxed oil and the diluent, passes through the filter element and flows into the control valve 38 and out through line 39, while the wax accumulates in the form 65 of a compact cake on the surface of the filter element 35. The continuous rotation of the filter drum 34 then brings the wet filter cake into the space above the slurry. Here, the wax may be optionally washed by naphtha or the like introduced through line 56, said washing agent, together with any oil adhering to the wax, being withdrawn from the system through valve 40 and line 41 provided with a valve 43.

Periodically, when the segmental walls 36 of 75

the filter drum 34 come in juxtaposition with walls 45 and 46 of chamber 47 the pressure in said chamber is suddenly released, as by opening valve 50 in line 49. This causes the evaporation 5 of the diluent in solution in the wax, and a rapid efflorescence of the wax. This wax is then scraped off by means of scraper 52, and removed from the system by means of scroll conveyor 53 and line 54.

10 It is to be understood that the above disclosures are not to be construed as limiting but merely as descriptive of the generic invention, since many variations may be made by those skilled in the art within the scope of the appended claims.

15 We claim:

1. A method for separating wax from wax-bearing oils which comprises commingling wax-bearing oil with a liquefied normally gaseous diluent, chilling the mixture to a temperature at 20 which wax precipitates from solution, filtering said chilled mixture to separate oil and diluent from the wax deposited in the filtration zone, withdrawing the separated oil and diluent from the filtration zone, suddenly evaporating the diluent still remaining in the filtered wax cake by reducing the pressure thereon and thereby causing the wax cake to become porous, expanded and easily friable and withdrawing the thus conditioned wax cake from said filtration zone.

2. A method as in claim 1 in which the pressure on the wax cake is reduced to a vacuum.

3. A method for separating wax from wax-bearing oils which comprises commingling wax-bearing oil with a liquefied normally gaseous diluent, chilling the mixture to a temperature at 35 which wax precipitates from solution, filtering said chilled mixture under superatmospheric pressure to separate oil and diluent from the wax deposited in the filtration zone, withdrawing the separated oil and diluent from the filtration zone, suddenly evaporating the diluent still remaining in the filtration wax cake by reducing the pressure thereon and thereby causing the wax cake to become porous, expanded and 40 easily friable and withdrawing the thus conditioned wax cake from said filtration zone.

4. A method as in claim 3 in which the evaporation of the wax cake is accomplished by releasing the pressure in the filtration zone.

5. A method as in claim 1 in which the diluent is a liquefied normally gaseous hydrocarbon.

6. A method as in claim 1 in which the diluent is liquid propane.

7. A method for separating wax from wax-bearing oils which comprises commingling wax-bearing oil with a liquefied normally gaseous diluent, chilling the mixture to a temperature at 10 which wax precipitates from solution, filtering said chilled mixture under a pressure of about 25 to 50 pounds per square inch to separate oil and diluent from the wax deposited in the filtration zone, withdrawing the separated oil and diluent from the filtration zone, suddenly evaporating the diluent still remaining in the filtered wax cake by reducing the pressure thereon and thereby causing the wax cake to become porous, 15 expanded and easily friable and withdrawing the thus conditioned wax cake from said filtration zone.

8. A method for separating wax from wax-bearing oils which comprises commingling wax-bearing oil with a liquefied normally gaseous diluent, chilling the mixture to a temperature at 20 which wax precipitates from solution, filtering said chilled mixture to separate oil and diluent from the wax deposited in the filtration zone, 30 withdrawing the separated oil and diluent from the filtration zone, heating the wax cake to a temperature sufficient to vaporize the diluent from the wax cake but to a temperature insufficient to melt the wax and thereby causing the wax cake to become porous, expanded and easily friable and withdrawing the thus conditioned wax cake from said filtration.

9. A method as in claim 8 in which the diluent is a liquefied normally gaseous hydrocarbon.

10. A method as in claim 8 in which the diluent is a liquid propane.
